CONCRETE MIXER

Frederick E. Mascetti and Americus D. Bruno,
Torrington, Conn.

Application May 18, 1932. Serial No. 612,019

4 Claims. (Cl. 83—73)

This invention relates to concrete mixers, and more particularly to a rotary drum type of concrete mixer divided into two compartments.

One object of this invention is to provide a concrete mixer of the above nature having two compartments, so that the raw or unmixed material may be placed in the first drum and mixed, while at the same time the material in the second drum may be mixed and delivered, thus reducing the required time of properly preparing concrete or other mixed ingredients about one-half.

A further object is to provide a mixer of the above nature having a novel means located upon the dividing partition of the drum for transferring the ingredients from the first compartment to the second compartment while the drum is being rotated.

A further object is to provide an apparatus of the above nature having means on the central partition to prevent any of the mixture from falling back into the first mixing compartment.

A further object is to provide a concrete mixer of the above nature which will be simple in construction, inexpensive to manufacture, easy to assemble and manipulate, compact, and very efficient and durable in use.

With these and other objects in view there has been illustrated on the accompanying drawing, one form in which the invention may be conveniently embodied in practice.

In the drawing:

Fig. 1 represents a longitudinal vertical sectional view of a concrete mixer embodying the invention.

Fig. 2 is a transverse sectional view of the same, taken along the line 2—2 of Fig. 1, looking in the direction of the arrows.

Fig. 3 is a detail fragmentary sectional view of the water-proof ball bearing construction for supporting the central diverter spout and splash guard.

Referring now to the drawing in which like reference numerals denote corresponding parts throughout the several views, the numeral 10 indicates a rotary mixing drum which is divided into two separate compartments by means of an annular central partition 11, thus forming a preliminary or "receiving" mixing chamber 12 and a final or "delivery" mixing chamber 13.

In order to rotatably support the drum 10, it has a pair of peripheral flanges 14 and 15 adjacent the front and rear end walls 16 and 17 thereof, said flanges being adapted to rest upon

the usual rollers 18. The rollers 18 are mounted upon a pair of longitudinal shafts 19 and 20 located under the drum 10 at opposite sides thereof. The opposite ends of the shafts 19 and 20 are suitably journaled in pillow blocks 21 supported upon a truck frame 22. The frame 22 is preferably mounted on wheels 23 so that the concrete mixer can be conveniently rolled around from place to place.

The drum 10 is adapted to receive its rotary motion by means of an annular gear or rack 24 surrounding the central part of the drum 10 and engaging a driving pinion 25 keyed to a driven horizontal shaft 26 located underneath said drum. The rear end of the driven shaft 26 is journaled in a hanger bearing 27 depending from a cross-channel iron 28 supported upon the truck frame 22. The front end of the driving shaft 26 may be connected to any suitable source of power, such as an internal combustion engine or electric motor (not shown).

The raw materials or ingredients for making concrete may be placed in the "receiving" mixing chamber 12 by means of an inclined chute 29 projecting through a flanged opening 30 formed in the center of the front end wall 16, and said ingredients are mixed in said chamber 12 by means of a plurality of longitudinally extending mixing scoops or buckets 31 angularly disposed within the chamber 12, and tending to deflect the mixture towards the rear of said chamber 12.

In order to shift the concrete mixture from the "receiving" chamber 12 to the "delivery" mixing chamber 13, provision is made of an arcuate shaped transferring chute or gate 32 pivotally journaled upon a pair of aligned shafts 33 and 34 which are threaded on their inner ends and screwed into an expansion nut 35, which nut functions similarly to a turn buckle. The chute 32, as shown in Fig. 1, is adapted to project partly within both chambers 12 and 13, the forward end of said chute 32, within the delivery chamber, having an arcuate-shaped inverted cover guard 36 securely attached to said chute, as by riveting. The cover guard 36 prevents any of the concrete mixture in the delivery chamber from falling into the chute 32, and from being thereby transferred back into the receiving chamber.

In order to support the chute 32 in a fixed position within the drum 10, preventing said chute 32 from rotating with said drum 10, the shafts 33 and 34, upon which said chute 32 is pivotally supported, are provided upon their opposite ex-

tremities with a pair of enlarged integral square shanks 37 and 38 engaged in similar shaped sockets formed in the inner periphery of the inner race 39 of a large water-proof ball bearing 40 mounted in the center of the partition 11, as shown in Fig. 1. The water-proof ball bearing 40 comprises an inner race 39, an outer race 41, and a series of equally spaced balls 42 adapted to move freely in a raceway 42a. The outer race 41 is adapted to be fitted within an annular seat 43 formed in an enlarged flanged rim 44 on the edge of the aperture in the partition 11, and said race 41 is held in said seat 43 against lateral movement by means of an annular retaining ring 45 secured to the rim 44, as by screws 46.

To retain lubricant within the ball bearing raceway 42a and also to prevent the access of water thereto, provision is made of a pair of annular packing rings 47 and 48, preferably made of compressed water-proof felt and located on opposite sides of the ball bearings 42 (see Fig. 3). The packing rings 47 and 48 are held in place by means of a pair of offset annular rims 49 and 50, and said packing rings 47 and 48 are preferably permanently secured to said rims 49 and 50, as by means of a plurality of rivets 51. The rims 49 and 50 are provided on their outer edges with integral inturned flanges 52 and 53 which are adapted to be slipped upon the shoulder formed in the outer race 43 and secured thereto, as by screws 54, as clearly shown in Fig. 3.

To swing the chute from the position shown in full lines to the diverting position shown in dotted lines in Fig. 1, provision is made of a rod 55 having a right-angle bend 56 at its inner end pivotally journaled in a lug 57 attached to the rear upper edge of the cover guard 36. The rod 55 extends through a flanged discharge opening 58 formed in the rear or delivery wall 17 of the drum 10, and is provided with a suitable handle member 59 for convenience in manipulation. The outer operating end of the rod 55 is supported in a loop bracket 60 secured to one of a pair of standards 61 mounted upon the rear extremity of the truck frame 22. If desired, the underside of the rod 55 adjacent the handle member 59 may be provided with a series of saw-toothed notches 62, adapted to be engaged by catch means (not shown) formed in the bracket 60 for the purpose of locking the transferring chute in any adjusted slanting position. It will be obvious from this construction that the chute 32, which is supported by the inner race 39 of the ball bearing 40, will be held against rotation by means of the rod 55, since said rod is secured to the stationary standard 61 outside of the rotating drum 10.

After the ingredients have been transferred from the chamber 12 to the chamber 13 by means of the chute 32, the mixture will be again agitated by a plurality of mixing scoops 63 angularly disposed on the inner wall of said chamber 13.

When the mixing of the concrete has been completed, it may be discharged from the delivery chamber 13 through the opening 58 by means of a discharge chute 64 supported upon a pair of swinging straps 65 which are pivotally journaled at their upper ends to a cross shaft 66, said shaft 66 being suspended between the upper ends of the standards 61.

Operation

In operation, when the driving mechanism

has been started to rotate the drum 10, the ingredients to be mixed may be introduced into the receiving mixing chamber by means of the chute 29. When the material has been mixed in the chamber 12 for about 37½ seconds, the central diverter chute will be shifted to the dotted line position as shown in Fig. 1, and the material falling from the scoops 31 will slide into the delivery mixing chamber 13, the time required for this shifting operation being about 10 seconds. The mixture will then be agitated in the chamber 13 for a similar period of 37½ seconds, and during this period, a fresh batch of ingredients will be introduced into the chamber 12. The completely mixed concrete may be readily discharged from the chamber 13 by merely swinging the chute 64 inwardly through the discharge opening 58 to the position shown in Fig. 1. This will cause the particles of the concrete mixture falling from the scoops 63 to be caught by said chute 64 and deflected out of the machine.

From this construction, it will be obvious that fully mixed concrete may be produced by the present improved apparatus in approximately one-half the time formerly required to thoroughly commingle it with the old type of single compartment drums, where it was necessary to wait the full time required for completely mixing before the batch of concrete could be discharged.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new and for which it is desired to secure Letters Patent is:

1. In a concrete mixer, a rotary hollow drum having inlet and outlet openings, a partition integral with said drum and having an opening therein, said partition dividing said drum into two compartments, means in said compartments for agitating the concrete mixture, a transfer chute pivotally supported by said partition and extending through said opening, a guard member attached to said chute to prevent said mixture from falling back from the second to the first compartment, a rod connected to said guard member for tilting said chute into operating position, and means for locking said rod in any adjusted position.

2. In a concrete mixer, a frame, a rotary hollow drum having inlet and outlet openings, a partition located within said drum and having an opening therein, a bearing ring mounted in said opening, a chute pivotally mounted in said ring for transferring concrete through said opening, means for swinging said chute into inoperative position, and means connected to said frame and said chute for preventing the rotation of the latter.

3. In a concrete mixer, a rotary hollow drum having inlet and outlet openings, a partition located within said drum and having an opening therein, a ball bearing raceway mounted in said opening, a chute pivotally mounted in said raceway for transferring concrete through said opening, means for swinging said chute into in-

operative position, and anti-friction means supported in said partition for preventing the rotation of said transfer chute.

4. In a concrete mixer, a base, a rotary hollow drum having inlet and outlet openings supported on said base, a partition within said drum dividing the same into receiving and delivery chambers, said partition having an opening, a ball bearing mounted in said opening, a chute pivotally supported in said ball bearing for transferring concrete from said receiving to said delivery chamber, means secured to said base

and rigidly connected to the pivotal support of said chute for swinging it about its axis and locking it in position, said means being adapted to prevent said chute from rotating, a guard member attached to said chute to prevent the mixed ingredients from passing back from the delivery to the receiving chamber, and means for discharging the mixed material from said delivery chamber.
